UNITED STATES PATENT OFFICE.

JAY R. SHRIVER, OF ELKHART, INDIANA.

RATCHET-WRENCH.

1,105,854.

Specification of Letters Patent.

Patented Aug. 4, 1914.

Application filed July 23, 1913. Serial No. 780,833.

To all whom it may concern:

Be it known that I, JAY R. SHRIVER, a citizen of the United States, residing at Elkhart, in the county of Elkhart and State of Indiana, have invented certain new and useful Improvements in Ratchet-Wrenches, of which the following is a specification, reference being had to the accompanying drawings.

10 This invention relates to new and useful improvements in wrenches, and more particularly to a ratchet wrench, and the primary object of the invention resides in providing a wrench of this character which may 15 be quickly and readily applied to use and which may be effectively operated with a minimum amount of energy on the part of the operator.

A still further object of the invention resides in providing a device which is simple 20 and durable in construction, inexpensive to manufacture and one which will be very efficient and useful in operation.

With these and other objects in view, the 25 invention consists in the novel features of construction, combination and arrangement of parts as will be hereinafter fully described and claimed.

In the accompanying drawings forming a 30 part of this application, Figure 1 is a plan view of the device complete. Fig. 2 is an elevation thereof showing the handle or shank member in section. Fig. 3 is a vertical section as seen on line 3—3, Fig. 1. Fig. 4 is a horizontal section as seen on line 4—4, Fig. 2. Fig. 5 is a similar view as seen on line 5—5, Fig. 2. Fig. 6 is a bottom plan view of the rotatable disk member removed from the device. Fig. 7 is an elevation 40 thereof. Fig. 8 is a section as seen on line 8—8, Fig. 3. Fig. 9 is a detail plan view of the eye member on the spanner portion of the shank or handle member; and Fig. 10 is a horizontal section as seen on line 10—10, Fig. 1.

In describing my invention, I shall refer to the drawing in which similar reference characters designate corresponding parts throughout the several views and in which 1 50 indicates a shank or handle member of elongated design, one end of which is curved or bent arcuately to form a spanner 2 that terminates in an eye 3. The other end of the shank 1 has an annular chambered head 4 formed thereon provided with a central opening 5. Mounted in the head 4, is a

socket embodying a disk 6 having centrally disposed bosses 7 and 7^a formed thereon extending from the opposite faces thereof. The boss 7 extends to a greater distance 60 beyond the disk 6 than the boss 7^a, the bore of the socket as a whole being polygonal. Fitting over the open end of the head 4, is a plate 8 which has a central opening therein to loosely receive the boss 7^a and lugs or the 65 like 9 formed on the peripheral edge of the plate 8 are adapted to register with similar lugs 10 formed on the peripheral edge of the head 4, whereby screws 11 may be inserted through the series of lugs to secure the plate 70 to the head and thus retain the socket in position therein.

Formed on one face of the head 4 and projecting outwardly therefrom, are the tubular teats 12, and arranged in each of the teats 75 is a coil spring 13. Also mounted in the teats 12 bearing against the coil springs 13, are pawls 14, the outer ends 15 of which are beveled. One face of the disk 6 has a circularly arranged series of inclined ratchet 80 teeth 16 formed therein and arranged to be engaged by the pawls 14. From this construction it will be seen that the pawls 14 are normally in contact with the ratchet teeth 16 so that when the head 4 is turned in one direction 85 the socket will be turned therewith, and when the head is turned in the opposite direction, the pawls 14 will readily ride over the inclined teeth 16 and have no effect whatsoever on the socket so far as the turning 90 of the same is concerned.

This wrench is particularly adapted for use in connection with fire plugs, wherein it is necessary to remove the cap in order to attach the hose. It will be seen that with 95 a device of this character, the cap may be quickly and readily removed from the plug and through the medium of the spanner on the opposite end of the handle or shank, the hose may be quickly and readily attached by 100 a single operator.

From the foregoing description of the construction of my improved device, the operation thereof will be readily understood and it will be seen that I have provided a device 105 which is simple and durable in construction, inexpensive to manufacture and one which will be very efficient and useful in operation.

While I have particularly described the 110 elements best adapted to perform the functions set forth, it is obvious that various changes in form, proportion and in the

minor details of construction may be resort-
ed to without departing from the spirit or
sacrificing any of the principles of the in-
vention.

- 5 Having thus described this invention,
what is claimed is:—

A wrench comprising a shank, an annular
chambered head projecting laterally there-
from, and provided with a plurality of tubu-
10 lar teats, the outer ends of which are closed
and the inner ends of which open into the
chamber of the head, coiled springs arranged
in the teats, pawls disposed in the teats and

projecting above the inner wall of the head,
a socket disposed within the head and hav-
15 ing a disk furnished on one side with ratchet
teeth to be engaged by the pawls, and a plate
fitting around one end of the socket and se-
cured to the head.

In testimony whereof I hereunto affix my 20
signature in the presence of two witnesses.

JAY R. SHRIVER.

Witnesses:

EDWARD B. ZIGLER,
CHAS. BILLGER.
